UNITED STATES PATENT OFFICE.

JAMES W. IVORY, OF PHILADELPHIA, PENNSYLVANIA.

DESIGN FOR A HANDLE FOR PUNCHES.

SPECIFICATION forming part of Design No. 28,739, dated May 31, 1898.

Application filed July 6, 1897. Serial No. 643,668. Term of patent 14 years.

To all whom it may concern:

Be it known that I, JAMES W. IVORY, a subject of the Queen of Great Britain, residing in the city and county of Philadelphia, State 5 of Pennsylvania, have invented and produced a new and original Design for the Handle of a Punch, of which the following is a specification, reference being had to the accompanying drawing, forming part thereof.

10 The leading feature of my design for the handle of a punch is a handle having a bifurcation at one end, a boss on one limb of said bifurcation, and an arm projecting from said limb as a continuity of said boss.

15 The drawing represents a perspective view of the handle of a punch embodying my design.

In the drawing, A designates the handle of a punch, at one end of which is the bifurcation B, formed by the limbs C D. On the 20 limb C are the boss E and the arm F, and on the other limb is the head G. The arm F is continuous of the boss E and extends outwardly therefrom as a continuity of the limb. 25

What I claim is—

The design for the handle of a punch substantially as shown and described.

JAMES W. IVORY.
